CROWN BLOCK

John M. Shimer, Dallas, Tex., assignor to Oil
Well Supply Company, Dallas, Tex., a corpo-
ration of New Jersey

Application August 10, 1935, Serial No. 35,677

4 Claims. (Cl. 254—190)

My invention relates to a crown block particularly of the center pin type for oil well derricks.

A crown block is mounted on the top or water table of a drilling derrick and provided with a number of sheaves over which the line of cable for supporting the travelling block is reeved. In drilling very deep wells by rotary drills the loads supported from the crown block are very heavy inasmuch as they comprise the hollow stem or pipe extending to the bottom of the well, the rotary drill and the supporting tackle. This necessitates the use of cable of large diameter and this in turn requires large diameter sheaves in order to prevent excessive bending and wear of the cable. Where a large number of sheaves are required, an excessive bending weight is imposed upon the pin or shaft supporting the sheaves and if an intermediate beam is used, the sheaves must be separated and thus moved out of direct alignment with the sheaves of the travelling block, so that a considerable side wear on the sheaves and cable takes place particularly when the travelling block is at or near the top of the derrick. Heretofore, double deck crown blocks have been used in order to obtain a compact reeving of the line, but this construction limits the diameter of certain of the sheaves and thus has the disadvantage of rapid wear of the cables, if large diameter cables are employed.

In my present invention I provide a center pin type of crown block with a support midway of or between the ends of the pin while maintaining a close spacing of the sheaves to approximate alignment with the travelling block sheaves which are spaced and with means close together to reduce the overall width to take up any side thrust that may be caused by a misalignment of the drilling shaft and also to permit an advantageous reeving of the cables for handling the drill stem or pipe. My invention also provides a crown block which can be easily and quickly mounted on the water table of the derrick.

The various features of my present invention are illustrated by way of example in the accompanying drawings in which—

Fig. 1 is a side view and Fig. 2 a vertical section on a plane parallel to that of Fig. 1 of a crown block embodying a preferred form of the invention; Fig. 3 is a vertical section through the crown block taken on line 3—3 of Fig. 2; Fig. 4 is a plan view of the crown block; Fig. 5 a vertical side view of a portion of the crown block, showing certain additional details; Figs. 6 and 7 are end views taken at the right

of Fig. 5 of portions of the crown block; Figs. 8 and 9 are diagrammatic showings of the reeving and travelling block for California and Mid-Continent rigs respectively, and Figs. 10 and 11 are diagrammatic views showing the position of the crown blocks in the California and Mid-Continent derricks.

In my present invention the sheaves of a crown block are rotatably mounted on a center pin which is supported at each end on the frame 10 of the crown block. The center pin is supported midway of the end supports by a truss member suitably flanged above the sheaves to provide sufficient rigidity and strength, but having a relatively narrow web in which the center pin 15 is mounted to avoid excessive spacing of the sheaves on opposite sides of the truss. The several sheaves are spaced by thrust plates at the hub portions to receive any side thrusts that may be imparted in the event of a bent grief 20 stem or kelly. The base of the crown block is made of a rectangular frame which may be spread apart to permit the center pin and its sheaves to be hoisted upwardly therethrough whereupon it may be closed to receive the supports of the center pin. A deflection sheave is 25 mounted on the frame so that the cable line may be reeved in such a manner that the travelling block may be guided by the derrick man with the slowest moving parts of the cable which 30 connect the crown block and travelling block nearest to him when in his regular position in the derrick for handling pipe.

Referring more particularly to the accompanying drawings, several sheaves 15, six being shown 35 by way of example, are rotatably mounted on a center pin 16 which is supported at each end in bearings 17 that rest upon the frame 18 of the crown block. The sheaves 15 are individually mounted on roller bearings 19 which are supplied 40 with lubricant through individual passages 20 in the center pin.

The center pin 16 is also supported midway of the bearings 17 by a truss 21, the ends of which rest on the frame 18 as shown at 22 in 45 Figs. 1 and 2. The truss 21 comprises a vertical web 23 reinforced by ribs 24 and is provided at its upper edge with flanges 25 that overlie the edges of the sheaves. The web 23 and reinforcing ribs 24 have much less thickness or width 50 than the flanges 25 and therefore permit a closer spacing of the sheaves than would be the case if an intermediate beam were employed, in which case the sheaves would be separated the full width of the flanges 25.

- The individual sheaves 15 are separated from the end bearings 17 and from the truss 21 and from each other by thrust plates 26 positioned between the hubs of the sheaves so as to take up side thrusts and wear that may result if the travelling block is thrown out of alignment with the crown block by a bending of the grief stem or by other causes. In this way an excessive wear-ing of the sheaves is avoided.
- 10 The supporting bearings 17 and the truss 21 are removably bolted on the frame 18 so that the center pin and its supports may be disassembled from the frame 18 and placed separately to the top of the derrick and installed. This is of great advantage because the total weight of the crown block is very great. In hoisting and assembling the crown block, therefore, the bearings 17 and the truss 21 are removed from the frame and the latter hoisted above and placed on the water table of the derrick and the center pin, sheaves and supports are then hoisted as a unit and set in position on the frame.
- 15 The frame 18 comprises a pair of longitudinally extending spaced beams 27 and a pair of connecting cross beams 28 bolted to the webs of the beams 27 by means of angle plates 29 and bolts 30. After the frame 18 has been placed on the water table, the bolts 30 at one end may be removed and the side beam 27 spread sufficiently to permit the center pin and its sheaves and supports to be hoisted upwardly through the opening. Thereupon the side beam 27 may be joined to the end beams 28 and the center pin and its sheaves lowered until the bases of the bearings 17 and the truss 21 rest in their proper position on the frame and are bolted thereto by means of bolts 31.
- 20 After the crown block has been installed on the top of the derrick or on the water table, a cable line 32 may be reeved about the sheaves 15 of the crown block and sheaves 33 of a travelling block as shown in Figs. 8 and 9. In the California type of rig, shown in Figs. 8 and 10, one end 34 of the cable line is passed around a deflecting pulley 35 and then secured to a calf wheel 36 at the base of the derrick. This is known as the dead end of the line. The other end 37 extends downwardly to the hoist 38. This is known as the live end of the line. In the 25 Mid-Continent type of rigging as shown in Fig. 9, the fixed or dead end 34 may be secured to the derrick and the travelling or live end 37 is secured to the hoist 38 as in the California type of rigging. With the California type of rig it will be apparent that those lengths of the cable line nearest the left of Fig. 8 and, therefore, nearest the moving end 37, travel at a greater speed than those to the right, where the supporting strands are nearest the fixed end of the line.
- 30 This is of advantage in the California type of rig, particularly, because the window of the derrick is at the left in a position shown in Fig. 10, as indicated at 39, and the lengths of the pipe or hollow drill stem are racked against the opposite side of the derrick as at 40, that is, at the right in Fig. 10, and the derrick man in guiding the travelling block 33 may do so by grasping the nearest parts of the cable line which are the slower moving lines. This is much easier and less dangerous than if the lines at this side of the derrick were the faster travelling lines.
- 35 It will be noted that there is a minimum of deflection of the lines between the crown block and the travelling block, because of the truss 21 and therefore a minimum deflection of the cable

even when the travelling block approaches the crown block. Consequently there is a minimum of side wear of the line against the grooved edges of the sheaves. The edges of the sheaves may be very closely spaced, but a fraction of an inch, 5 so there is no danger of the cable falling between the sheaves and a very compact arrangement is obtained.

The deflecting pulley 35 may be mounted in a bracket 41 at one of the longitudinal beams 27. 10 Similarly a cat line sheave 42 may be mounted on a bracket 43 secured by clamps 44 to a lower flange of one of the beams 27 as shown in Figs. 5 and 6.

A sand line sheave 44' may also be mounted on 15 a bracket 45 on one of the cross beams 28, as shown in Figs. 5 and 7, when the crown block is used in a Mid-Continent rig as shown in Figs. 9 and 11. When the crown block is to be used for a California type rig, the sand line sheave 46 20 may be mounted in a bracket 47 secured to a web of one of the beams 27, so as to align with the window of the derrick.

By the above invention, therefore, I have provided a multiple sheave heavy duty crown block 25 having a center pin that is supported intermediate its ends without an intermediate beam that would cause a wide spacing of the sheaves on opposite sides of the beam and thus a displacement from alignment with the sheaves of the 30 crown block. Excessive wear on the grooves of the sheaves and on the cable is thus avoided. Excessive wear between the sheaves is avoided by the use of the thrust plates which take up any such thrust that may be caused in the event that 35 the grief stem should throw the travelling block out of alignment. The invention also provides a very compact crown block that may be readily mounted on the derrick and which permits the reeving of the cable so as to place the most 40 slowly travelling lengths nearest the derrick man for guiding the travelling block.

The weight and stresses on the crown block are distributed equally at the bearings for the center pin and at the ends of the truss therefor, 45 distributing the stresses equally at four points spaced at angles of 90° from each other. This will be apparent because the center pin being uniformly loaded, one-half of the load will be taken by the truss at the center of the center pin and 50 distributed equally at the two ends of the truss, and the remaining one-half will be equally distributed to the two bearings of the center pin.

What I claim is:

1. A multiple sheave crown block having a 55 center pin, sheaves mounted on said pin, a supporting frame having a pair of spaced bearings, one at each end of said pin, a truss between said bearings supported on said frame and supporting said center pin intermediate said bearings, said 60 truss extending above said sheaves and having a flange extending partly over said sheaves.

2. A multiple sheave crown block having a center pin, sheaves mounted on said pin, a supporting frame having a pair of spaced bearings, 65 one at each end of said pin, a truss between said bearings supported on said frame and supporting said center pin intermediate said bearings, said truss having a relatively thin web and ribs between said sheaves and a wider flange above the 70 sheaves.

3. A multiple sheave crown block having a center pin, sheaves mounted on said pin, a supporting frame having a pair of side members mounted so that they may be spread apart to 75

5 permit the passage between them of said pin and sheaves and replaced, a pair of bearings, one at each end of said pin, to be supported on said members, a truss between said bearings supported on said members and supporting said center pin intermediate said bearings, said truss extending above said sheaves and having a flange above and overlapping said sheave.

4. A multiple sheave crown block comprising a 10 frame consisting of side and cross pieces joined together to form an integral supporting structure,

a sheave pin, means providing bearing supports for the ends of said sheave pin on the top of said side pieces midway between said cross pieces, means providing a center support for said pin on top of said cross pieces midway between said side pieces, a plurality of sheaves on said pin equally divided on opposite sides of said central support, and a plurality of spacer elements separating said sheaves from each other and from said bearing and center support means. 5
